UMBILICAL CORD CLAMP

John Dickinson Schneider, Deerfield, Ill., assignor to
Hollister Incorporated, Chicago, Ill., a corporation of
Illinois

Filed Dec. 1, 1960, Ser. No. 63,068

Term of patent 14 years

(Cl. D83—12)

FIG. 1 is a side elevational view of an umbilical cord clamp embodying my new design;

FIG. 2 is a front elevational view thereof;

FIG. 3 is a view taken perpendicular to the top thereof;

FIG. 4 is a transverse cross-sectional view thereof taken on line 4—4 of FIG. 1;

FIG. 5 is a fragmentary view showing the top of the lower member thereof;

FIG. 6 is an enlarged fragmentary bottom perspective view of the front of the lower member thereof;

FIG. 7 is an enlarged fragmentary top perspective view of the front of the bottom member thereof; and

FIG. 8 is a side elevational view thereof in closed position.

I claim:

The ornamental design for umbilical cord clamp, as shown.
